(57) **CLAIM**

The ornamental design for an end cap, as shown and described.

DESCRIPTION

FIG. 1 is a top, front, right perspective view of a first embodiment of an end cap showing our new design; FIG. 2 is a top, front, left perspective view thereof; FIG. 3 is a bottom view thereof; FIG. 4 is a top view thereof; FIG. 5 is a rear view thereof; FIG. 6 is a front view thereof; FIG. 7 is a right side view thereof; FIG. 8 is a left side view thereof; FIG. 9 is a top, front, right perspective view of a second embodiment of an end cap showing our new design; FIG. 10 is a top, front, left perspective view thereof; FIG. 11 is a bottom view thereof; FIG. 12 is a top view thereof; FIG. 13 is a rear view thereof; FIG. 14 is a front view thereof; FIG. 15 is a right side view thereof; and, FIG. 16 is a left side view thereof. The broken lines immediately adjacent to the shaded area define the bounds of the claimed design and form no part thereof. The broken lines depicting the remainder of the end cap show features that form no part of the claimed design.

1 Claim, 16 Drawing Sheets
